UNITED STATES PATENT OFFICE

2,115,271

SIGNAL

Frederick J. La Londe, Virginia, Minn.

Application May 22, 1937, Serial No. 144,176

2 Claims. (Cl. 116—63)

This invention relates to signaling devices and has special reference to improvements in a portable danger signaling device the principal object being to provide as convenient and compact 5 a portable signaling device as possible, and one which may be readily carried about as for example in a truck or other vehicle frequently traversing a highway and subject to the necessity for such.

10 It is well known that the majority of states require the placing of danger signals some considerable distance in both directions on a highway from a stalled or wrecked truck, and to provide a novel and convenient instrumentality of this type 15 is a further object of the invention.

Other objects and advantages of the invention will appear in the following description thereof.

Referring now to the accompanying drawing, forming part of this application, and wherein like 20 reference characters indicate like parts:

Figure 1 is a front view of one embodiment of the invention with the upper hinged portion of the front of same elevated and partly broken away.

25 Figure 2 is a combined side and central sectional view, the lower portion of the housing being shown in section.

The preferred form of housing is of rectangular form, narrow, and with the side walls converging 30 somewhat, forming a top materially less in the width than the bottom, and upon which top is mounted a suitable handle for carrying the device about. The back wall of the housing is shown at 1, the lower fixed portion of the front 35 wall is indicated at 2, the bottom of the housing at 3, and the upper hinged portion of the front wall at 4. The hinges of this swinging portion of the front wall are illustrated at 6, they being fastened to the top as indicated so that the whole interior of the housing is readily accessible by opening 40 this swingable front portion.

At the union of the swinging portion and the fixed portion of the front wall are two spaced circular openings, half of each circular opening being cut 45 in each abutting edge, the lower marginal walls of which are indicated at 7 and 8 and the upper marginal walls of these circular openings occur in the lower edge of the swinging portion. Directly back of each of these openings and fixed to the back wall is attached a reflector button or disc 9 and visible, ordinarily, through their respective openings when the door of the housing is closed.

In the upper portion of the housing and attached to the back thereof is a clock mechanism

indicated at 10, from the front of which is suspended a pendulum, the rod of which is indicated at 11 and the pendulum itself at 12. These as well as the clock mechanism may be of any desired construction, the essential element being that the pendulum itself is preferably slightly larger than either the discs 9 or the openings 7 and 8 in the front of same, and the swinging of the pendulum there, when in action, alternately obscures and exposes the discs 9 as viewed 10 through the openings 7 and 8. Thus when the device is placed upon a highway, for example, facing in the direction of oncoming traffic and the clock is operated in alternately flashing on and off the reflector discs, they are visible to the 15 driver of an approaching vehicle and very effectively caution him of the existing danger.

As a means for compensating for irregular conditions of the pavement or surface of the highway where such a device may be used, I have shown 20 an auxiliary base, preferably round in construction and of two separable parts, hinged for example as at 13 upon one side of an upstanding integral socket indicated at 14, the opposed protruding halves 15 of the socket being upright with 25 a suitable wing nut 16 for pinching the depending ball 17 formed integral with the bracket 18 attached to the bottom of the housing of the device previously described. Thus this auxiliary base 30 may be normally held tightly pinched against the depending ball of the housing so that when the signal is placed for example on a pavement it may be slightly off plumb, which the pendulum of the clock will readily indicate, when the attendant may tip the body portion of the device 35 in any direction to bring about a plumb condition of the pendulum and thus insure good operation of the clock mechanism without further attention, and thereby providing an adequate danger signal.

Having thus described my invention, what I claim and desire to secure by Letters Patent, is:

1. A portable danger signaling device comprising 45 a vertically elongated receptacle having a relatively large flat bottom and a handle attached to the upper end thereof for convenient transportation of same, spaced light reflecting units in the back of the lowermost portion of said receptacle, similarly sized and spaced openings in the front wall of said receptacle, said reflecting units being visible only through said similarly sized and spaced openings, a pendulum suspended within the receptacle and of a size to alternately hide said reflectors from view and means within 50 55

the upper portion of said receptacle for rhythmically swinging said pendulum.

2. A portable danger signal including a housing having spaced reflectors therein, similarly sized and spaced openings in the front wall of said housing, said reflectors being alternately visible

through said similarly sized and spaced openings, a pendulum swingable back and forth in front of said reflectors and between them and said openings in front of same, and means for operating said pendulum in cadence.
